UNITED STATES PATENT OFFICE.

LEE W. V. WILMS, OF CHICAGO, ILLINOIS.

SELF-ACTING FOOT-ARCH SUPPORT.

1,320,952.

Specification of Letters Patent.

Patented Nov. 4, 1919.

Application filed June 21, 1919. Serial No. 305,815.

To all whom it may concern:

Be it known that I, LEE W. V. WILMS, a citizen of the United States, and resident of Chicago, in the county of Cook and State of Illinois, have invented certain Improvements in Self-Acting Foot-Arch Supports, of which the following is a specification.

My present invention relates to improvements in foot supporting devices of the type which are insertible in complete shoes, and it consists in certain peculiarities of the construction, novel arrangement and operation of the various parts thereof, as will be hereinafter more fully set forth and specifically claimed.

The principal object of the invention is to provide a self-conforming or adjusting insert for shoes or a foot support, which shall comprise as a unit, means to support all of the tarsal bones, the articulations of the tarsal and metatarsal bones of the human foot, as well as to furnish reinforcement therefor at points where the greatest strain occurs in the support for the foot.

Numerous other objects and advantages of the invention will be disclosed in the following description and explanation.

In the accompanying drawing which serves to illustrate an embodiment of the invention,

Figure 1 is a plan view of a self-adjusting arch support embodying the invention, showing by dotted lines the normal positions of the metal supporting plates occupied with respect to the leather or flexible supporting member for said plates.

Fig. 2 is a bottom plan view of the device showing by dotted lines about the positions to which the metal supporting plates may shift themselves and occupy under the pressure of the foot of the wearer.

Fig. 3 is an inner edge view of the support, and

Fig. 4 is a cross sectional view taken on line 4—4 of Fig. 2 looking in the direction indicated by the arrows.

Corresponding numerals of reference refer to like parts throughout the different views of the drawing, in which it will be seen and understood that the device shown therein is for the right foot, it being deemed unnecessary to show the device for the left foot, as it would be the same as those shown, except that the parts thereof would be located in the opposite directions or reversely.

As shown, the support consists of an upper plate or supporting member 6, for the peculiarly and novel shaped metal plates, which supporting member is by preference made of leather, and substantially of the form in outlines as shown in the drawing. This plate supporting member 6 is somewhat larger and longer than the combined length of the metal supporting plates 7 and 8, which are secured thereto in the manner to be presently explained and conforms to the upper surfaces of said metal plates, although it is wider than the latter and has at its inner portion a longitudinally and upwardly extended arched flange 9, of greater dimensions than the longitudinally arched portion of the inner edges or parts of the metal plates 7 and 8, as will be readily understood by reference to the different views of the drawing.

The plates 7 and 8 are made of any suitable kind of spring or resilient metal, but by preference of German silver. The plate 7, which will be called the intermediate plate, is slightly and downwardly dished at its heel portion, as indicated at 10 in Fig. 3 of the drawing, and is longitudinally and upwardly arched from the front portion of its dished part to its front end, which end terminates transversely with respect to the supporting member 6 at a point about half way between the base and the heads of the metatarsal bones when the device is in use.

The anterior or the front portion of the plate 7, is preferably transversely arched and, as before stated, the leather covering or supporting member 6 for the metal plates is correspondingly arched above the same, as will be understood by reference to Figs. 2 and 3 of the drawing. This plate 7, is secured at its rear inner portion near its inner edge, and in the front portion of the depression or dish shaped part thereof by means of a single rivet 11 to the member 6, near its inner edge, and in the front portion of the depression therein, which corresponds or conforms to the depression 10 of the plate 7, which plate supports all of the tarsal bones and the articulations of the tarsal and the metatarsal bones. Secured at one of its ends to the intermediate plate 7 near the middle portion thereof in front of the depression or dished portion 10 of the same is the lower metallic plate 8, which is longitudinally and upwardly arched as is clearly shown in Fig. 3 and is slightly

transversely and downwardly arched at its rear portion where it is secured by a rivet 12 to the plate 7, but not at this point to the leather covering or supporting member 6.

The plate 8 or lower plate extends forwardly from its pivoted or secured portion to near the front end of the member 6 and terminates at said end at a slight distance 10 from the front end of the member 6 in a slightly widened and transversely arched portion to support the anterior transverse arch of the foot. This plate furnishes reinforcement where most of the strain usually 15 falls on a support for the foot. The front inner portion of the plate 8 is secured to the member 6 by means of a rivet 13, which as shown in Figs. 1 to 3 of the drawing, is located near the front inner edges of the plate 20 8 and the member 6, and near the front and inner corner of the intermediate plate 7, which latter plate and the plate 8 are loosely connected together by means of the rivet 12 or other suitable fastening device.

25 As shown, the rear end of the member 6 is curved to fit snugly in the heel portion of the shoe, and as above set forth, and as shown, the intermediate plate 7 is downwardly dished at its rear portion to receive 30 the correspondingly shaped portion of the member 6, which construction will provide protection against injury to the flesh tissue of the foot at the heel thereof, which often occurs or is occasioned by the heel nails of 35 the shoe.

The inner margin or edge of the intermediate plate 7 is provided with a slightly upturned and longitudinally extended flange 13 which extends from a point near 40 the anterior portion of the heel, os-calcis bone, forwardly to about the front end of said plate and reinforces the upwardly extended and longitudinally arched flange 9 of the member 6 to which the plate 7 is secured at its rear inner portion.

In use, the support, with its members 6, 7 and 8, being formed to fit in a general and corrective way under the sole of the foot of the wearer, is placed in the shoe in such 50 a way that the rear curved portion of the member 6 will fit in the upright portion of the heel of the shoe and lie on the sole thereof. By placing the shoe on the foot in position for wearing the same, it is obvious that 55 when downward pressure is applied to the member 6 and through it to the plates 7 and 8, the latter, by reason of the pivotal action of the intermediate plate 7 through the instrumentality of the rivet 11 with the flexible member 6, and through the medium of the rivet or connection 12 with the lower plate 8, which plate is connected near its front inner portion to the member 6, will have independent movement of each other 60 thus permitting the plates to automatically

adjust themselves to different positions, as shown by dotted lines in Fig. 2 of the drawing, to properly support feet of various lines and shapes. As the supporting member 6 is made of leather or other suitable 70 flexible material, it will of course have some elasticity so that the distances between the points 11, 12 and 13 will be slightly varied under the pressure of the foot, thus permitting the intermediate plate 7 to shift its 75 position with respect to the support 6 and lower plate.

Having thus fully described my invention, what I claim as new and desire to secure by Letters Patent, is,—

1. A device of the character described, consisting of a suitably shaped elongated supporting and foot rest member, an elongated resilient plate secured near one of its side edges and one of its ends to the said 85 member near one of its side edges and ends for slight lateral movement, the said plate and member having substantially the same shaped plan surfaces, and another elongated resilient plate underlying the first named 90 plate and extended beyond one of the ends of the latter and secured near one of the side edges to the said member at a distance from the free interposed end of the first named plate, said second named plate having 95 substantially the same shaped plan surfaces as the said member and first named plate.

2. A device of the character described, comprising a flexible member adapted to 100 directly support the foot, an intermediate plate of resilient material secured near its rear inner portion to the lower surface of the flexible member at a corresponding position, said plate being provided in its rear portion with a downwardly dished part 105 and longitudinally and upwardly arched from the front portion of said dished portion and terminating at its front with a transversely and upwardly arched portion, 110 and a lower plate secured near its rear end to the intermediate plate and near its front end to the flexible member, said lower plate being upwardly and longitudinally arched and having an upwardly and transversely 115 arched portion in its front part.

3. A device of the character described, comprising a flexible elongated member adapted to directly support the foot, an intermediate plate of resilient material secured near its rear inner portion to the lower surface of the flexible member at a corresponding position for slight lateral movement with respect to said member, said plate being longitudinally and upwardly 120 arched from near one of its ends to its other end and having a transversely and upwardly arched portion in its front part, and a lower plate secured near its rear end to the intermediate plate and near its front end to the 125 130

flexible member, said lower plate being upwardly and longitudinally arched and having an upwardly and transversely arched portion in its front part.

5 4. A device of the character described, comprising a flexible elongated member adapted to directly support the foot and having at its inner edge a longitudinally and upwardly arched flange, an intermediate plate of resilient material secured near its inner portion to the lower surface of the flexible member at a corresponding position, said plate being provided in its rear portion with a downwardly dished part and longitudinally and upwardly arched from the

front portion of said dished part and terminating at its front with a transversely and upwardly arched portion, said plate also having at its inner edge an upwardly and longitudinally arched flange underlying and 20 reinforcing a portion of the flange of said flexible member, and a lower plate secured near its rear end to the intermediate plate and near its front end to the flexible member, said lower plate being upwardly and 25 longitudinally arched and having an upwardly and transversely arched portion in its front part.
